Ex Parte Quayle Office Action, dated Jun. 26, 2019, for Design U.S. Appl. No. 29/683,761, filed Mar. 15, 2019.

Primary Examiner — Michael C Stout*Assistant Examiner* — Fitzgerald L Butac(74) *Attorney, Agent, or Firm* — Haynes and Boone, LLP**CLAIM**

The ornamental design for an oilfield frac pump, as shown and described.

DESCRIPTION

FIG. 1 is a top left perspective view of an oilfield frac pump that embodies the ornamental design;

FIG. 2 is a front elevation view of the oilfield frac pump;

FIG. 3 is a rear elevation view of the oilfield frac pump;

FIG. 4 is a right side elevation view of the oilfield frac pump;

FIG. 5 is a left side elevation view of the oilfield frac pump;

FIG. 6 is a top plan view of the oilfield frac pump; and,

FIG. 7 is a bottom plan view of the oilfield frac pump.

The broken lines show portions of an oilfield frac pump that form no part of the claimed design.
